[57] CLAIM

The ornamental design for a communication headset, as shown and described.

DESCRIPTION

FIG. 1 is a perspective view of a communications headset showing our design;

FIG. 2 is a side elevational view thereof;

FIG. 3 is a top plan view thereof;

FIG. 4 is a bottom plan view thereof;

FIG. 5 is a front elevational view thereof;

FIG. 6 is a rear elevational view thereof; and,

FIG. 7 is an opposite side elevational view thereof.

The perspective view of FIG. 1 is an alternative position for use. The broken line showings of FIG. 1, 2, 5, 6, and 7 are for illustrative purposes only and form no part of the claimed design.
